CLAIM

The ornamental design for a display screen or portion thereof with graphical user interface, as shown and described.

DESCRIPTION

FIG. 1 is a front view of an electronic device with a display screen showing the claimed design;

FIG. 2 is a rear view thereof;

FIG. 3 is a left side view thereof;

FIG. 4 is a right side view thereof;

FIG. 5 is a top view thereof; and,

FIG. 6 is a bottom view thereof.

The inner dash-dot-dash broken-line rectangle in FIG. 1 shows the perimeter of a display screen and forms no part of the claimed design. The remaining dash-dot broken lines in the figures show portions of an electronic device and form no part of the claimed design.

The dash-dash broken lines in FIG. 1 illustrate portions of the graphical user interface and form no part of the claimed design.

For purposes of clarity, the graphical user interface is shown as it would appear on the display screen and is used to display information and parameters for a medical imaging system, such as a Magnetic Resonance (MR) imaging system.
